UNITED STATES PATENT OFFICE.

THEODORE C. BULLOCK, OF GRAND JUNCTION, COLORADO.

ROAD-GRADER.

1,363,454.

Specification of Letters Patent. Patented Dec. 28, 1920.

Application filed May 14, 1919. Serial No. 297,053.

To all whom it may concern:

Be it known that I, THEODORE C. BULLOCK, a citizen of the United States, residing at Grand Junction, in the county of Mesa, 5 State of Colorado, have invented certain new and useful Improvements in Road-Graders; and I do hereby declare the following to be a full, clear, and exact description of the invention, such as will enable 10 others skilled in the art to which it appertains to make and use the same.

This invention relates to scrapers, and more especially to those which are sledged; and the object of the same is to produce a 15 road grader whose scraper is reliably but adjustably mounted across and between two spaced sleds.

The invention lies particularly in the details of connection between the draft beam 20 of the front sled and the scraper, so that the load thrown onto the latter when at work is communicated directly to the draft; and the invention lies further in the specific connection of the two sleds by arches consisting 25 of strap irons in pairs bolted to their runners and which serve also as guides for the scraper when it is adjusted. Reference is had below to the accompanying drawings forming a part of this application, wherein 30 like characters designate corresponding parts throughout the several views, in which—

Figure 1 is a side elevation of my improved road grader.

Fig. 2 is a plan view thereof.

Fig. 3 is a transverse section taken on the line 3—3 of Fig. 2.

Fig. 4 is a detailed view of the adjustment means for the scraper blade showing the 40 same in a differently adjusted position from that shown in Fig. 1.

Fig. 5 is a detailed sectional view of one of the throw levers.

Referring to the drawings in detail, my 45 improved road grader is shown mounted upon a supporting frame indicated in general by the numeral 10, the same including a forward sled 11 and a rear sled 12 having suitable platforms mounted upon runners 50 13 and 14, and 15 and 16 respectively to which the platforms are secured. The runners are also connected by cross braces 17 so as to provide a rigid structure, said braces being disposed adjacent to transverse connecting or frame members 18.

The runner 13 extends rearwardly of the runner 14 and both are provided with for-

wardly inclined or beveled rear ends as shown at 19, the same being undercut on rectilinear lines for a purpose to be herein-after made apparent. The runner 15 which is disposed in alinement with the runner 13 terminates in spaced relation to the runner 13 in the rear thereof and is shorter than the runner 16 which is disposed in alinement with the runner 14 so that the forward ends of the runners 15 and 16 are equidistantly spaced in rear of the runners 13 and 14 respectively and have their forward ends rounded as shown, the spaces between the 60 runners being designed to accommodate the scraper blade as will be later described. The transverse frame members and the brace rods 17 and 18 respectively are disposed parallel to each other and at right angles to the 65 runners and are disposed to the rear ends of the runners 13 and 14 and adjacent to the forward and rear ends of the runners 15 and 16 and spaced from the bottom edges of the 70 runners as shown.

At their forward ends, the runners 13 and 14 are connected by a transverse draft beam 20 preferably having U-bolts 21 for connection of a draft pole 22 therewith through the medium of a transverse bar 23 having hooks 24 for engaging the U-bolts 21, which latter are disposed through the draft beam 20. This provides means for attaching the draft animals, although I desire to have it understood that any suitable form of draft 80 means may be provided for advancing the machine or device.

The draft bar or beam 20 is rigidly braced to the runners 13 and 14 at the forward ends of the latter by reinforcing strips 25 disposed upon the inner and outer sides of the runners and secured thereto as by means of suitable securing means 26 passing through the runners and connecting the opposed strips which latter having their forward 90 ends directed inwardly at right angles as shown at 27 against the forward and rear faces of the beam 20 so as to accommodate the ends of the latter therebetween. The portions 27 are secured by fastening means 100 105 28 passed through the beam 20, thus giving the required strength for all necessary draft pull.

The strips 25 are extended beneath the platform of the front sled 11 and have their rear ends turned upwardly in ears as shown at 29 above the top edges of the runners 13 and 14 and equidistantly spaced from the rear ends thereof so as to be located diag-

onally across the sled or so that a line connecting the pivots will be parallel to a line connecting the rear ends of the runners 13 and 14. The strips 25 of each runner are however, located in parallel relation and their ears apertured to receive pivot pins 30 by which the forward ends of beams 31 are pivotally connected on horizontal axes for vertical movement to swing above the top edges of the runners 13 rearwardly of the pivots, while the rear ends or shanks of the beams are curved downwardly between the sleds for the attachment of the scraper including a plate 32 and a blade 33 at the lower edge thereof.

Alined runners are connected by spaced pairs of intermediately and upwardly arched straps 34, the arched portions being located between the runners at each side and each pair being disposed in alignment transversely of the frame, while the beams 31 and their shanks are similarly related to support the scraper in a diagonal position beneath the arches of the straps 34, which latter have their forward and rear extremities horizontally extended and secured to opposite faces of the alined runners. The connecting arches are thus disposed in pairs above the top edges of the runners and receive the beams 31 therebetween for vertical swinging movement, the horizontal portions of the connecting beams being disposed near the bottom edges of the runners and bracing the latter vertically adjacent to their spaced ends so as to form a rigid connection which in effect produces a single sled comprising the transporting frame for supporting and advancing the scraper and having spaces or bottom recesses for accommodating the blade.

In order to adjust the scraper vertically to bring its blade into and out of engagement with the ground and to hold the same in adjusted position, one of each pair of connecting beams carries a notched segment 35 and pivoted to the same beams, near their lower ends, are adjustable throw levers 36 having said lower ends extended downwardly for pivotal connection with the shank portions of the beams 31 by pivoted links 37. Each throw lever carries a catch mechanism including a housing 38 preferably stamped from a section of sheet metal in substantially rectangular formation and retained in position by pins 39, with integral ears 40 bent over the edges of the levers at the sides opposite to the sides upon which the housings are disposed, said housings also having depending projections 41 serving to guide the levers in their swinging movements. Mounted in each housing is a latch comprising opposed pairs of strips 42 spaced apart intermediately to straddle the pins 39 and joined at their ends to provide engaging portions designed to fit the notches of the

segments, while the links 43 connect their opposite ends to pivoted latch handles 44 mounted upon the levers at their gripping portions. Springs 45 serve to hold the catches engaged and they may be disengaged by the catch handles so that the levers may be swung on their pivots to raise or lower the scraper blade parallel to or angularly with respect to the ground, downward movements of the levers at their free ends which project over the platform of the sled 12 and runners 15 and 16, causing upward movement of the opposite ends of the levers and the links connected thereto so as to raise the blade and vice versa. By this means the blade can be very easily controlled and positively held in an adjusted position so as to give proper action upon the rod bed. A suitable brake bar 46 is pivoted to one of the runners, preferably the runner 16 at its outer side and adjacent to the rear end thereof in convenient position to be controlled by the operator upon the rear sled 12, so as to check the side lash of the scraper or grader as desired.

By this construction power applied to the beam 20 is led back through the strips 25 and beams 31 directly to the scraper, so that resistance on the latter when at work is thrown onto the draft rather than onto the sled. It is known that oblique scrapers produce considerable side lash, and in order that this may be resisted, the shanks of the beams 34 are passed between the arches and the straps of the latter are bolted to both sides of the alined runners. The result is that the two sleds become practically one, and their cross bars and the boards of their platforms are strictly transverse as shown in Fig. 2.

What is claimed is:

The herein described road grader comprising two tandem sleds having their respective runners alined and spaced, straps bolted to opposite sides of said runners in pairs and arched over the space between them, a draft beam at the front end of the forward sled, reinforcing strips leading from this beam along and secured to both sides of the front runners and having upturned spaced ears at their rear ends, beams pivoted between said ears and having their rear ends turned downward and movably mounted between the arches of the respective pairs, a scraper carried by their down-turned ends and standing oblique to the line of draft, and means for adjusting the position of said scraper vertically at each end.

In testimony whereof, I affix my signature, in the presence of two witnesses.

THEODORE C. BULLOCK.
